UNITED STATES PATENT OFFICE.

IVAR RENNERFELT, OF DJURSHOLM, SWEDEN.

ELECTRIC FURNACE.

Application filed March 3, 1921. Serial No. 449,388.

To all whom it may concern:

Be it known that I, IVAR RENNERFELT, a citizen of the Kingdom of Sweden, and resident of Djursholm, in the county of Stockholms Lan and Kingdom of Sweden, have invented certain new and useful Improvements in Electric Furnaces, of which the following is a specification.

My invention relates to improvements in the construction of an electrically heated crucible furnace and has for its objects to provide a furnace especially suitable for utilizing a granulated resistance for heating a crucible, the muffle of a heat-treating furnace or some other hollow or solid object.

It is previously well known in the art, that a crucible may be heated by surrounding it by for instance crushed coke or graphite and passing an electric current through said coke or graphite, which acts as a resistance generating a considerable amount of heat in the space surrounding the crucible. It has, however, heretofore not been possible to successfully use two- or three-phase current in such furnaces. This is a disadvantage, especially if the power required is not rather small, because in most cases an unbalanced singlephase load is not permitted on a polyphase distribution system.

It is also generally necessary to use a rather low voltage or to use an external resistance in series with the furnace, as it is impractical for many reasons to arrange the said resistance with a comparatively small cross section in connection with a substantial length as required for using a voltage as commonly obtainable.

In order to attain the objects of my invention I propose to arrange the heating resistance as strings alongside of the crucible or muffle. If the furnace is to utilize three-phase current, the number of resistance strings should be three, separated from each other by suitable means.

It is also possible to change the number of phases from 3 to 2 by a special transformer, as is well known in the art. If this is done, only two strings are required. If single phase current is available, only one string may be used or two strings in parallel or in series with each other.

The muffles of hardening furnaces are as a rule closed at one end. The top and bottom

sides of the muffle are considerably wider than the other side. To heat a muffle of this kind I prefer to arrange one string of heating resistance on the top side and one underneath the bottom side. The strings may be directly joined behind the end wall of the muffle and two-phase- or single phase current may be employed. If the muffle is to be open at both ends, the strings can not have a common contact behind the end wall, but in such a case the strings may be connected together by means of a ring of resistance material surrounding the muffle a short distance from the end.

The muffle may be used in a vertical as well as in a horizontal position.

If the muffle is to be used as a crucible for melting purposes, the furnace may be arranged to tilt in the usual way so as to facilitate discharging of the contents.

Openings should be provided at suitable places, permitting inspection and renewal of the resistance material, when required. The material of which the crucible or muffle is to be made, should be a good conductor of heat but not of the electric current. The melting point should for obvious reasons be as high as possible. Consequently bonded carborundum, "carbofrax C," silica or possibly a high grade fire clay would be well suitable for the purpose.

According to this invention it would be possible to construct a furnace having a plurality of crucibles arranged in a line parallel to each other and separated from each other by means of layers of resistance material. It is obvious that in such a case it is not necessary, that the cross section of the crucibles is flattened as the circular form may also be used, if certain precautions are observed so as to separate and insulate the heating resistances from each other. A furnace having a plurality of crucibles heated according to the principles disclosed in this specification should prove very suitable for solving several metallurgical problems involving the generation of heat without fuel. The furnace should, thus, be well adapted for making iron sponge, for reducing tin, zinc, copper and other metals from their combinations with oxygen or other elements.

In the accompanying drawing several furnaces in modified forms are illustrated. Figure 1 is a vertical cross section on the

line X—X. Fig. 2 and Fig. 2 is partly a vertical cross section on line y—y Fig. 1, partly an end view. Said figures illustrate a furnace having a muffle with rectangular or oval cross section open at one end. The furnace may be used in both horizontal and vertical position. Fig. 3 is a vertical cross section of a furnace having a plurality of horizontal muffles arranged above each other. The same figure may represent a horizontal cross section of a furnace having a plurality of vertical muffles arranged in a line one after the other. The muffle in Fig. 3 may be open at only one or at both ends. Fig. 4 is a cross section of a furnace having a circular muffle, heated on two sides by separate resistances. Fig. 5 is a cross section of a furnace having a muffle of triangular cross section, heated by means of resistance units corresponding to each side. Fig. 6 is a vertical cross section of a furnace in which a plurality of muffles placed side by side are heated by means of a string of resistance material below and on top of the crucibles. The section is taken at z—z in Fig. 7, which is a cross section at v—v in Fig. 6. This figure may also represent a horizontal cross section at z—z in Fig. 7. In this case the muffles are standing upright with their bottoms down. The space between the muffles and the furnace walls is completely filled with resistance material. Similar numerals refer to similar parts throughout the several views.

In Figs. 1 and 2 a flat muffle is indicated with 1. Between the furnace wall 2 and the muffle resistance material is indicated with 3. This resistance does not surround the muffle on all sides, but only on a part of the flat surfaces being in contact with the muffle on the top side, but not necessarily touching the lower side of the muffle. The resistance passes also behind the bottom of the muffle as indicated in Fig. 1. Electric current is admitted to the heating resistance by means of contacts 4, f. i., of carbon projecting into the resistance. If two-phase current is to be used, the contact behind the bottom of the muffle (to the left in Fig. 1) is to be connected to the common point of the two phases. If single phase current is to be used the said contact may be omitted but it may also be used for connecting the upper and lower resistances in parallel with each other. In this way a certain regulation of the generation of heat may be obtained. The space between the furnace wall and the muffle should be closed by doors 5 at either end of the furnace permitting the inspection of the heating chamber and also refilling of the resistance material, when required. To facilitate this the furnace may be raised to an upright position, the resistance material being simply dropped into the heating chamber. The

contacts 4 should be watercooled in suitable manner, if required.

In Fig. 3 a plurality of muffles 1 have been arranged above each other inside of a furnace wall 2 and separated by means of layers of resistance material 3. The muffles are preferably flattened or oval in cross section. Electric current is admitted in any preferred manner by means of contacts 4 projecting into the heating resistance. The type of furnace illustrated by Fig. 3 offers certain advantages when the floor space is limited. The thermal efficiency also is improved as the heat-losing surface is considerably reduced in comparison with the volume of the muffles. If so desired it is also possible to arrange the muffles of this type in vertical position. Fig. 3 would then represent a horizontal cross section.

In Fig. 4 a modified form of the furnace Figs. 1 and 2 is illustrated. The furnace 2 in this case is provided with a cylindrical muffle 1, heated by means of two resistances 3, one on each side and separated from each other by means of an insulating wall 6. Contacts 4 are provided for admitting electric current to the resistance. According to Fig. 5 the muffle of a furnace built as indicated in Fig. 4 may be modified by giving it a triangular cross section. To each side of the muffle corresponds a strip of resistance running alongside the muffle. The three resistances may be conveniently connected to a three-phase power net. The resistances may be connected in star or delta as desired.

In Figs. 6 and 7 another modification is illustrated, which is provided with a plurality of muffles 1 arranged side by side in a furnace 2 and adjoining each other. The heat is generated by means of a resistance on the top side of and another resistance underneath the muffles. The resistance in this modified form is running crosswise to the length of each separate muffle but lengthwise if all individual muffles are considered as a unit. The resistances are provided with contacts 4 for admitting current in any preferred manner.

It is obvious that both direct and alternating current may be used in furnaces as described in this specification. The furnaces are independent up to a certain limit of the voltage available and also of the frequency.

Having now fully described, my invention, I claim:

1. In an electric furnace the combination of an elongated crucible with a plurality of strings of carbonaceous resistance material located lengthwise along the crucible, electrically insulating material separating the strings from each other and means for conducting electric energy to the resistances.

2. In an electric furnace the combination of an elongated crucible with a plurality of

strings of carbonaceous resistance material located lengthwise along the crucible, electrically insulating material separating the strings from each other a common connection between the strings at one end of the crucible and means for conducting electric energy to the opposite ends of the strings.

Signed at Stockholm in the county of Stockholms Lan and State of Sweden this 12th day of February, A. D. 1921.

IVAR RENNERFELT.
